UNITED STATES PATENT OFFICE.

PHINEAS B. SWICK, OF TECUMSEH, MICHIGAN.

SHAFT-TUG.

SPECIFICATION forming part of Letters Patent No. 297,727, dated April 29, 1884.

Application filed February 23, 1884. (No model.)

To all whom it may concern:

Be it known that I, PHINEAS B. SWICK, a citizen of the United States, residing at Tecumseh, in the county of Lenawee and State of Michigan, have invented certain new and useful Improvements in Shaft-Tugs, of which the following is a specification, reference being had therein to the accompanying drawings.

This invention has relation to improvements in that class of devices known as "shaft-tugs;" and it consists in the novel construction and arrangement of the same, as will be hereinafter more fully explained, and particularly pointed out in the appended claim.

The annexed drawings, to which reference is made, fully illustrate my invention, in which—

Figure 1 represents a vertical sectional view of my shaft-tug. Fig. 2 is a face view of the same, and Fig. 3 is a face view of the tug un-looped.

Referring by letter to the accompanying drawings, A designates the tug, which consists of a single strap, the upper portion, a, of which is broad and the lower portion narrow, as shown at b. The upper portion, a, is provided with a buckle, c, that connects with the strap of a harness-saddle, and the strap b buckles to the shaft-girth of the harness. The broad portion a is provided with a transverse slot, d, and below which and on the outer face of the tug-strap is secured by rivets a metal plate, B, at each end of which are formed loops e, through which the girth end of said tug-strap passes.

When the device is in position for use, the strap b is passed through the slot d from the inside outwardly, thence through the loops e

e on the ends of the metal plate aforesaid, thus forming a tug or a loop, f, through which the shaft of the vehicle is passed and supported.

It will thus be observed from the above description that the tighter the girth is drawn the more firmly will the tug secure itself to the shaft, thus holding it securely, and should the breeching break, the vehicle could not run on the animal, and if a trace should break, or likewise a single-tree, the animal could not become disengaged from the shafts, and the metal plate, with its end loop, serves to prevent the shafts or thills from vertical movement, as would be the case otherwise; and a shaft-tug constructed as herein shown and described is durable, neat in appearance, easily operated, and at the same time cheap to manufacture.

Having described my invention, what I claim, and desire to secure by Letters Patent, is—

The improved shaft-tug herein described, consisting of the single strap A, having the broad loop portion a, narrow strap portion b, the transverse slot d, and the buckle c, and provided with the plate B, secured on the outer face of the loop portion, having end loops, e, to receive the strap b after the latter is passed through the slot d in forming the shaft-loop f, the whole constructed and arranged as shown, described, and for the purpose set forth.

In testimony whereof I affix my signature in presence of two witnesses.

PHINEAS B. SWICK.
